UNITED STATES PATENT OFFICE.

FREDERICK W. COLLIER, OF WORCESTER, MASSACHUSETTS, ASSIGNOR OF ONE-THIRD
TO HAMBLIN & RUSSELL MFG. COMPANY, OF WORCESTER, MASSACHUSETTS, A COR-
PORATION OF MASSACHUSETTS.

STRAINER.

1,286,235.

Specification of Letters Patent.

Patented Dec. 3, 1918.

Application filed June 3, 1915, Serial No. 31,976. Renewed June 3, 1918. Serial No. 238,032.

To all whom it may concern:

Be it known that I, FREDERICK W. COLLIER, a citizen of the United States, residing at Worcester, in the county of Worcester,

5 State of Massachusetts, have invented a certain new and useful Improvement in Strainers, of which the following is a specification, reference being had therein to the accompanying drawings.

10 This invention relates to sieves or strainers, but more particularly to such as are provided with a handle and has for its object to produce a structure which is more simple and efficient than any device of a similar nature heretofore constructed.

15 One embodiment of the invention is shown in the drawings in which:

Figure 1 is a side elevation of the invention complete.

20 Figs. 2 and 3, detail views illustrating the method of constructing the invention, as will be fully described hereinafter.

Fig. 4, central vertical section, as will be fully described hereinafter.

25 Fig. 5, enlarged transverse section through the band, as will be fully described hereinafter.

Referring to the drawings the invention is shown to comprise a band 10 of sheet metal 30 which has its lower edge 11 turned upwardly to form an interlocking joint with the corresponding turned down edge of the fabric 12 which performs the straining. This method of securing the band to the wire fabric is best shown in Fig. 5 of the drawings, but as such formation is well known in the art no further description thereof is here deemed necessary.

35 Indentations 13 are cut in the upper ring 40 of the band for the purpose which will be fully described hereinafter. The sieve holder is here formed with a wooden handle 14 in which is inserted the wire shank 15 here formed integral with the ring 16 45 adapted to fit around the band 10. The band is first bent in the usual manner as shown in Fig. 2 and the ends secured. Then the ring 16 is slipped over this band in the manner shown in Fig. 3. The edge 50 17 of the band is preferably then turned

about this ring in the manner shown in Figs. 4 and 5 so that this ring is tightly bound to the upper edge of the band and such band is reinforced thereby.

55 In the ring 16 are preferably formed bends or loops 18 adapted to project from the band in the manner shown in Fig. 1 so that when the strainer is placed over a bowl or dish, it will be supported upon the rim thereby and the shank of the handle. Indentations 13 are located on the band opposite to these projections so that when the band is turned about the ring 16 these projections extend therethrough as does the shank in the handle. The fabric is then 60 locked to the band in the manner described. If ribs 19 are desired to protect the fabric, additional indentations 13 are provided for the opposite ends of each of these ribs and they may be soldered or otherwise fastened 70 to the ring 16 at the points on the ring exposed by these indentations as is shown in Fig. 1 of the drawings.

75 While these strainers are usually made in semispherical form it should be clearly understood that the structure is not limited to such form or to any particular method of securing the fabric to the band, for these may be varied as desired and form no part of the present invention.

80 What I claim as my invention and desire to secure by Letters Patent is:—

1. In a device of the class described, a sheet metal band having its upper edge indented at certain points, a wire ring fitting 85 about said band and having the upper edge of the band rolled over said ring in locking engagement therewith, said ring having formed thereon certain projections adapted to extend through the corresponding indentations in the turned edge of the band to act as supporting members, and straining cloth attached to said band.

90 2. In a device of the class described, a strip of sheet metal bent to form a supporting rim, the upper edge of said rim being notched at certain points, a wire ring fitting about said band and having the upper edge of the band rolled over the ring 95 in locking engagement therewith, a handle 100

- formed on said ring and projecting through a notch in the turned edge of said band, a wire cloth vessel having its upper edge secured to the lower edge of said band, and
5 supporting ribs beneath said vessel having their upper extremities engaging said ring through certain of the notches in said band.

In testimony whereof I affix my signature in the presence of two witnesses.

FREDERICK W. COLLIER.
